(57) **CLAIM**

The ornamental design for a cooking vessel, as shown and described.

DESCRIPTION

FIG. 1 is a front perspective view of an embodiment of a cooking vessel showing our design;

FIG. 2 is a front view of the embodiment of the cooking vessel;

FIG. 3 is a rear view of the embodiment of the cooking vessel;

FIG. 4 is a left side view of the embodiment of the cooking vessel;

FIG. 5 is a right side view of the embodiment of the cooking vessel;

FIG. 6 is a top side view of the embodiment of the cooking vessel; and,

FIG. 7 is a bottom side view of the embodiment of the cooking vessel.

The shade lines in the figures show contour and not surface ornamentation.
